UNITED STATES PATENT OFFICE

157,359

CARPET

Robert Fleck, Jenkintown, Pa., assignor to C. H. Masland and Sons, Carlisle, Pa., a corporation of Pennsylvania

Application August 5, 1949, Serial No. 4,315

Term of patent 14 years

(Cl. D92—4)

To all whom it may concern:

Be it known that I, Robert Fleck, a citizen of the United States, resident of Jenkintown, Montgomery County, Commonwealth of Pennsylvania, have invented a new, original, and ornamental Design for Carpet, of which the following is a specification, reference being had to the accompanying drawing, forming a part thereof.

The figure is a plan view of the face of the carpet, embodying my new design.

The back of the carpet is plain, and the design is visible only on the face.

A design unit is outlined by broken lines. Said design unit is repeated over the carpet as indicated.

I claim:

The ornamental design for a carpet, as shown and described.

ROBERT FLECK.
